UNITED STATES PATENT OFFICE.

GUSTAF ARVID ANDERSON, OF BALTIMORE, MARYLAND, ASSIGNOR TO THE T. H. SYMINGTON COMPANY, OF NEW YORK, N. Y., A CORPORATION OF DELAWARE.

CAR TRUCK.

1,414,920.

Specification of Letters Patent. Patented May 2, 1922.

Application filed January 22, 1921. Serial No. 439,096.

To all whom it may concern:

Be it known that I, GUSTAF ARVID ANDERSON, a citizen of the United States, residing at Baltimore, in the State of Maryland, have 5 invented certain new and useful Improvements in Car Trucks; and I do hereby declare the following to be a full, clear, and exact description of the invention, such as will enable others skilled in the art to which 10 it appertains to make and use the same.

My invention relates to trucks for railway cars and particularly to a form of flexible truck having side frame members whose relative longitudinal displacement from normal or square position is controlled by 15 spring means tending to return the side frames toward normal relation. More particularly the invention is concerned with a truck structure of the character indicated in 20 which the spring means for controlling longitudinal movements of the side frames is simple in construction, efficient in operation and well adapted either to oppose longitudinal displacement of the side frame members 25 from normal position throughout a portion only of such displacement, as is preferred, or continuously to oppose said displacement throughout its full extent. In either case 30 the initial resistance offered by the spring means in opposition to the longitudinal movements of the side frame members may be made as great as desired since the spring means is constructed in a manner which readily allows the springs thereof to be 35 assembled under an initial compression. The particular embodiment of the invention illustrated in the drawing is an advantageous one in that the spring means by which relative longitudinal movements of the side frames 40 are regulated is well adapted to serve with truck side frame members of various designs now in use.

One of the principal features of my invention, generally stated, consists in controlling the relative longitudinal movement 45 of the truck side frames by spring means which are spaced from the respective frame members when the truck is in square but which are called into action to resist relative 50 longitudinal displacement of the frames only after the latter have been displaced a predetermined distance from normal, a short unrestrained longitudinal movement of either side frame thus being attained. A 55 further primary feature of the invention

consists in providing means for yieldingly resisting relative longitudinal displacement of the truck side frame members from normal position with a plurality of springs which are spaced longitudinally of the truck 60 and are dissimultaneously compressible transversely thereof.

There are other features of the invention relating to details of elemental construction and particular combinations of parts, all as 65 will hereinafter appear.

In the drawings which illustrate the preferred embodiment of the invention, the scope whereof is pointed out in the claims.—

Figure 1 is a view, partly in plan and 70 partly in horizontal section, of a car truck containing the invention, the bolster, which is of the type commonly employed in flexible trucks, being omitted and the truck parts being shown in a position such as they as- 75 sume when the truck passes around a curve.

Figure 2 is a detail view, partly in plan and partly in horizontal section, showing the relation of the spring means to the cross connecting member of the truck and one of 80 the side frames, the parts being in normal position.

Fig. 3 is a detail section on the line 3—3, Fig. 2, the cross connecting means of the truck and the plunger or operating member 85 for one of the springs being in elevation.

Figure 4 is a detail section on the line 4—4, Fig. 2.

Figure 5 is a detail view, partly in plan and partly in horizontal section, of a modified form of my invention showing the spring means as normally contacting with the side frame members. 90

In the drawings, 1 indicates transversely spaced side frame members which are relatively movable longitudinally of the truck. 95 Each side frame is provided at its opposite ends with journal boxes 2 receiving the journal ends of the axles 3 upon which the wheels 4 of the truck are mounted.

The side frame members 1 are movably connected across the truck by suitable connecting means 5 which may conveniently constitute a truck spring plank. When constructed as a spring plank the opposite ends 105 of the cross connecting means 5 may extend into the respective bolster openings 6 of the side frames and there be pivotally connected to said frames 1. The pivotal connection of the spring plank with the side frames may be 110

simply effected by providing each side frame centrally of its bolster opening with an upwardly projecting pivot boss 7 which extends into a corresponding pivot opening 8 of the spring plank. Sufficient clearance is provided between the sides of the spring plank 5 and the neighboring faces of the columns 9 of the side frames to allow the spring plank to turn freely through an angle corresponding to the maximum relative longitudinal displacement from normal which it is desired that said side frames 1 shall have. As is usual in flexible trucks the truck bolster also has sufficient clearance from the truck columns 9 to permit it to angle horizontally without binding upon the latter when the side frames 1 are displaced longitudinally to their full extent from square relation.

20 A plurality of yielding means 10 may advantageously be employed for resisting longitudinal displacements of the side frame members away from their square relation, said means being preferably wholly mounted 25 upon the spring plank 5 adjacent their respective side frames 1 and in spaced relation transversely of the truck. While such is the preferred construction it is apparent that a single spring means may be employed if desired to resist relative longitudinal displacement of the side frames away from square relation and to effect their relative longitudinal movement toward normal position.

Each spring means 10 for resisting displacement of the side frame members from normal preferably comprises a housing 11 riveted to the spring plank 5 and having a plurality of parallel longitudinally spaced spring pockets 12 which extend transversely 40 of the truck and respectively receive springs 13. The walls 14 and 15 of the spring pockets form abutments for the springs 13 which are adapted to be energized by reciprocating plungers 16 whose stems extend through 45 apertures 17 in the outer walls 15 of the housing and whose heads or followers 18 bear against the ends of the respective springs 13. In both embodiments of my invention the springs 13 are preferably forced 50 into the pockets 12 so as to place the springs under an initial compression. In the modified form of construction shown in Fig. 5 the initial compression of the springs is preferably augmented in assembling the side 55 frames with the cross connection 5 so as to force the plunger heads 18 inwardly from the adjacent abutments 15. This additional compression of the springs 13 automatically compensates for wear upon the reciprocating 60 plungers 16.

While, as illustrated in the modified construction shown in Fig. 5, the stems of the plungers 16 may be of a length sufficient to enable them to engage the adjacent side 65 frame 1 when the truck parts are in normal

position, it is preferred, as is shown in Figs. 1, 2 and 3, to make the stems of the reciprocating plungers of such length that they stand in spaced relation to and a short distance from the proximate side frame member 1 when the truck is in square. This not only relieves the ends of the plungers 16 from wear due to frequent but inconsequential displacements of the side frames from normal position but also by allowing a small unrestrained displacement of the side frames from normal prolongs the life of the spring mechanisms 10.

When a truck such as hereinbefore described passes around a curve the track resistance applied to it causes a relative displacement of the side frames 1 longitudinally so that the truck is thrown out of square. When this displacement of the frame members has proceeded sufficiently to cause the spring plank 5 to be returned through an angle large enough to bring the end of one of the reciprocating plungers 16 into engagement with the neighboring side frame, further relative movement of the frame members in an out of square direction causes those plungers which are in engagement with the side frames to move transversely of the truck, thus, through their respective plunger heads or followers 18 compressing the springs 13 with which they severally cooperate. The springs 13 of each of the yielding means 10 are dissimultaneously energized, that is to say, one of said springs is compressed when the adjacent side frame 100 moves in one direction from normal while the other spring is similarly compressed upon movement of the side frame in the opposite direction.

In the modified form of construction illustrated in Fig. 5 the springs 13 of each yielding unit 10 are likewise independently and dissimultaneously energized, but unlike the case of the construction shown in the principal figures of the drawing, the compression 110 of one or the other of these springs takes place immediately upon the side frame members 1 moving from their square relation.

I claim:

1. In a car truck, the combination with 115 side frame members which are relatively movable longitudinally of the truck, of means for movably connecting said side frame members, and means for yieldingly resisting relative longitudinal displacement 120 of said side frame members from normal position throughout a portion only of said displacement from normal.

2. In a car truck, the combination with 125 spaced side frame members which are relatively movable longitudinally of the truck, of means extending transversely of the truck for connecting said side frame members, and means mounted on said connecting means and adapted to permit a free relative lon- 130

gitudinal movement of either side frame from normal position for a predetermined distance and to oppose resistance to further displacement from normal position of either

5 side frame.

3. In a car truck, the combination with side frame members which are relatively movable longitudinally of the truck, of means for movably connecting said side frame members, and spring means adapted to resist relative longitudinal displacement of said side frame members, said spring means being spaced from one of said side frame members when said frame members

10 are in square relation but being adapted to engage and to resist longitudinal displacement of said frame member when the latter has been displaced a predetermined distance longitudinally of the truck from normal po-

20 sition.

4. In a car truck, the combination with transversely spaced side frame members which are relatively movable longitudinally of the truck, of means pivotally connected at 25 its opposite ends to said side frame members, and means carried by said truck and adapted yieldingly to oppose relative displacement of either of said frame members, said yielding means being normally spaced

30 from one of the side frame members and being adapted to exert pressure upon the latter when the angle between said side frame member and said connecting means exceeds a predetermined amount.

35 5. In a car truck, the combination with side frame members which are relatively movable longitudinally of the truck, of a member movably connecting said side frame members, and spring means adapted to restrain relative longitudinal displacement of said side frame members, said spring means being mounted upon one of said members and normally being spaced from another of said members and being active to oppose relative longitudinal displacement of said side frame members.

45 6. In a car truck, the combination with side frame members which are relatively movable longitudinally of the truck, of means for movably connecting said side frame members, and means for yieldingly resisting relative longitudinal displacement

50 of said side frame members from normal position throughout a portion only of said displacement from normal, said last named means involving a plurality of longitudinally spaced parallel springs each of which

55 is independently compressible.

60 7. In a car truck, the combination with side frame members which are relatively movable longitudinally of the truck, of means for movably connecting said side frame members, and means for yieldingly resisting

relative longitudinal displacement of said side frame members from normal position throughout a portion only of said displacement from normal, said last named means involving a spring extending transversely of

70

the truck and compressible upon a relative longitudinal displacement of said side frame members away from normal position.

8. In a car truck, the combination with side frame members which are relatively movable longitudinally of the truck, of means for movably connecting said side frame members, and means for yieldingly resisting relative longitudinal displacement of said side frame members away from normal position, said last named means involving a plurality of dissimultaneously compressible spaced springs extending transversely of the truck, and a spring abutment member having pockets adapted respectively to receive

80

85

90 9. In a car truck, the combination with side frame members which are relatively movable longitudinally of the truck, of means for movably connecting said side frame members, and means for yieldingly resisting relative longitudinal displacement of said side frame members away from normal position, said last named means involving spring abutment means having a plurality of pockets, a plurality of springs respectively arranged in said pockets, and a plurality of reciprocating members corresponding to said springs and adapted to energize the latter.

100

105 10. In a car truck, the combination with side frame members which are relatively movable longitudinally of the truck, of means for movably connecting said side frame members, and means for yieldingly resisting relative longitudinal displacement of said side frame members away from normal position, said last named means being mounted upon said connecting means and involving a spring abutment member having a plurality of pockets, a plurality of springs respectively arranged in said pockets, and a plurality of spring actuating members movably mounted upon said abutment member and extending toward one of said side frame members and adapted to actuate said springs.

110

115 11. In a car truck, the combination with side frame members which are relatively movable longitudinally of the truck, of a spring plank pivotally connected at its opposite ends to said side frame members, and a plurality of means for yieldingly resisting relative longitudinal displacement of said side frame members away from

120

125

normal position throughout a portion only of said displacement from normal, each of said means being wholly mounted on said spring plank adjacent a corresponding one of said side frame members and including

130

a spring and means operatively interposed between said spring and the adjacent side frame member for energizing said spring by a longitudinal displacement of said side frame from normal position.

12. In a car truck, the combination with a plurality of side frame members which are relatively movable longitudinally of the truck, of a spring plank pivotally connected at its opposite ends to said side frame members, and a plurality of means for yieldingly resisting relative longitudinal displacement of said side frame members away from normal position, each of said means be-

ing mounted upon said spring plank adjacent a corresponding one of said side frame members and including a spring abutment member having a plurality of spaced pockets, a plurality of transversely extending springs respectively arranged in said pockets, and a plurality of reciprocating members corresponding to said springs and movably mounted on said abutment member and extending toward the adjacent side frame member and adapted to be actuated by the latter.

In testimony whereof I affix my signature.
GUSTAF ARVID ANDERSON.
